UNITED STATES PATENT OFFICE.

PHILIP YOE, OF CINCINNATI, OHIO, AND JOHN KIRBY, JR., OF LUDLOW, KENTUCKY.

PADLOCK.

SPECIFICATION forming part of Letters Patent No. 275,970, dated April 17, 1883.

Application filed October 20, 1882. (Model.)

To all whom it may concern:

Be it known that we, PHILIP YOE and JOHN KIRBY, Jr., both citizens of the United States, residing respectively at Cincinnati, in the county of Hamilton and State of Ohio, and Ludlow, in the county of Kenton, in the State of Kentucky, have invented a new and useful Improvement in Padlocks, of which the following is a specification.

10 Our invention relates to that class of spring-padlocks from which the key cannot be withdrawn after the shackle has been thrown open until it is again closed and locked.

15 We are aware that padlocks have been made to retain the key, after having been unlocked, until the shackle is again closed and caught by the detent, as shown in Letters Patent No. 198,713, for instance, but in such locks as heretofore constructed the key has been free to turn 20 on its post, but is held immovable until the shackle shall have been closed to locking position. This has been found to be a serious fault, especially for railway use, as persons not familiar with the construction of the lock are 25 apt to apply sufficient force to break the key in endeavoring to extract it.

Our invention consists essentially in securing 30 to the face of the main tumbler a thin plate or lug working in close proximity to the front wall of the case, and provided with a longitudinal slot to adapt its sidewise movement when the key is inserted, and a vertical slot for 35 the admission of the lip of the key, so that when the key is turned in the lock it carries the tumbler and its attached plate upward, (and sidewise,) thus shifting the retaining plate or lug, so that its vertical slot will no longer register with the key-hole, hence preventing 40 the withdrawal of the key.

45 In order that our invention may be fully understood, we will proceed to describe it with reference to the accompanying drawings, in which—

Figure 1 is a perspective view of a padlock 50 with the face-plate removed, showing the shackle locked and the key free to be withdrawn, the vertical slot in the retaining plate or lug being in register with the key-hole. Fig. 2 is a side elevation of a padlock, showing in dotted lines the shackle open and the vertical

slot in the retaining-plate out of register with the key-hole. Fig. 3 is a perspective view of the tumbler and retaining-lug removed from the case. Fig. 4 is a perspective view of the tumbler and another form of retaining-lug, also removed from the case.

55 A represents the tumbler, pivoted on a post, B, and having an arm, a, extending beyond said post. To the face of the main arm of this tumbler is secured a thin plate or lug, C, working in close proximity to the face-plate of the case, and having a longitudinal slot, c, in its center and a transverse slot, c', extending at right angles to the main slot c. The slot c is made the width of the diameter of the stem of 60 the key, and is of sufficient length to allow the necessary sidewise movement, and the slot c' the width and length of the bit D of the key. The bit D is of such height that it can turn freely under the retaining-lug without contact 65 therewith. A shackle, F, is pivoted at g, and has a supplemental arm, f, extending downward beyond said pivot, working in connection with the rear arm, a, of the tumbler A. A spring, H, is coiled at its center around a 70 hub, h, the upper end bearing against the back part of the arm f of the shackle F, so as to throw the shackle open when its arm f is released by the arm a of the tumbler, and the other end bears against the under side of the 75 arm a of said tumbler to throw it up in front of the arm f, thus preventing the opening of the shackle until the key shall have been turned.

80 Supposing the parts to be in the position shown in Fig. 1, (or locked in position,) the operation is as follows: When the key is turned the bit passes under the retaining plate or lug C and bears upward against the under side of the arm A of the tumbler, swinging it on its 85 pivot, thereby carrying up the main arm A and the retaining-lug C and depressing the supplemental arm a. This depression of the supplemental arm a releases the arm f of the shackle, and the upper arm of the spring H, bearing 90 against the back of said arm f, swings the shackle on its pivot g, thereby opening it and throwing its arm f forward, so as to engage on the top of the arm a and hold it in its depressed position, the parts being then in the 95 100

position shown in Fig. 2. The operation of the parts thus separately described are simultaneous. It will be seen that the key is now free to turn in the cast, it being out of contact with all the working parts, and that it cannot be extracted until the shackle is again closed, when the parts will resume their position shown in Fig. 1. This construction may be varied without departing from the nature of our invention.

Fig. 4 shows a modification in the construction of the retaining-lug, in which an arm, N, is pivoted to the side wall of the lock, and is formed with a lug, M, under which the key may pass, and which, when the tumbler is raised, stands across the key-hole to prevent the withdrawal of the key. The arm is operated by the tumbler, and is held in contact therewith by suitable detaining-lugs.

Having thus described our invention, the following is what we claim as new therein and desire to secure by Letters Patent:

In a padlock, a key-retaining lug or projection formed on the face of the tumbler, or an arm thereof, and adapted, when the tumbler is raised, to engage over the bit of the key to prevent its withdrawal, while permitting it to be freely turned on its post, without contact with any of the working parts, when the shackle is open, substantially as set forth.

The foregoing specification of our invention signed by us this 9th day of October, A.D. 1882.

PHILIP YOE.
JOHN KIRBY, JR.
